To all whom it may concern:

Be it known that I, Isidor Doctor, a citizen of the United States of America, residing in Chicago, county of Cook, and State of Illinois, have invented a new, original, and ornamental Design for a Dress, of which the following is a specification, reference being had to the accompanying drawing, forming part thereof:

Fig. 1 is a front view of a dress showing my new design.

The characteristic feature of my design resides in the combination of contrasting materials to form a checkered effect on the yoke of the dress. The element at the base of the neckline consists of a rhinestone clip.

I claim:

The ornamental design for a dress, substantially as shown and described.

ISIDOR DOCTOR.
